H. STRACHE
PROCESS FOR THE COMPLETE GASIFICATION OF BITUMINOUS FUELS IN
ALTERNATELY OPERATED GENERATORS
Filed August 6, 1921

Inventor
Hugo Strache
by A. B. Foster

Attorney

UNITED STATES PATENT OFFICE.

HUGO STRACHE, OF VIENNA, AUSTRIA.

PROCESS FOR THE COMPLETE GASIFICATION OF BITUMINOUS FUELS IN ALTERNATELY-OPERATED GENERATORS.

Application filed August 6, 1921, Serial No. 490,364, and in Austria June 28, 1916.

(GRANTED UNDER THE PROVISIONS OF THE ACT OF MARCH 3, 1921, 41 STAT. L. 1313.)

The new process of the present case relates to a complete gasification process without leaving any carbonaceous residue, in generators operated alternately (that is, air and steam being admitted in alternate steps) in which the distillation chamber or retort is in direct communication (see Austrian Patent 27211 of Aug. 15, 1906,) with the gasification chamber or generator, without the interposition of any cut-off device, and in which the distillation gas produced in the retort during the period of blowing up the fuel (with air) to incandescence is utilized, either by a suitable arrangement for the air supply or gas discharge or by being stored in a storage chamber (see Austrian Patent 71698 of Oct. 15, 1915).

In the processes hitherto used and based on this principle, steam was continuously blown in, at the lower portion only of the generator, during the process of producing gas, and the distillation or degasification of the bituminous fuel was carried out partly by heating from the outside by means of the producer or blast gas being generated (when the fuel was blown up to incandescence), and partly by the heating from the inside by the hot ascending water gas.

The degasification may now be materially augmented if steam be also blown in at that point of the apparatus where the distillation chamber or retort merges into the generator chamber. This also materially augments the formation of ammonia.

The steam may also be used in a superheated state, and for this purpose it is allowed to flow through the heating flues surrounding the retort, which also prevents the collection of combustible gases in the flues during the process of gasification and for the further increase of its temperature, a separate steam superheater (which may be conveniently heated by the producer gas formed when the fuel is being blown up to incandescence) may be employed. In this case a large volume of steam in a slightly superheated state may be employed and thereby a higher yield of ammonia obtained. The temperature, of course, must not be carried above the decomposition temperature of the ammonia.

In this way it is also possible to effect the

distillation of the fuel by superheated steam alone, which is introduced at the place where the distillation chamber or retort and the generator chamber join each other, so that in this case it is not necessary to pass the water gas, formed in the generator chamber, through the fresh fuel. In this case the water gas is taken off at the lower part of the generator and the supply of steam from below is dispensed with. In this case therefore only distillation gas containing a high percentage of ammonia is produced in the distillation chamber or retort by superheated steam and led away at the top, while steam simultaneously passes through the column of coke in the generator chamber from top to bottom and forms water gas, which is led away at the bottom. The two gases may then be purified in the usual way, separately from each other, and used separately or mixed in any desired manner. The purification of the gases separately has also the advantage, that the apparatus for removing the tar and the ammonia may be considerably smaller than when the whole of the gas mixture (which has a much larger volume) has to be treated therein. If it be desired to pass a portion only of the water gas through the retort in order to promote the distillation of the fuel, the steam intended for the generation of the water gas is passed in at about the middle of the generator, so that a portion thereof passes downwards and forms water gas which is taken off at the bottom while another portion passes through the upper part only of the generator chamber and then passes through the retort in the form of water gas.

In cases where the steam is supplied partly at the top and partly at the bottom, adjustment of the separate steam supplies is necessary. This adjustment may be conveniently effected by measuring the differences in pressure at a convenient point, and throttling the steam flow at such point, and as the whole of the steam not yet superheated is more easily measured than the separate currents of superheated steam, the measurement of the whole of the steam may be conveniently effected before the introduction thereof into the superheater, and the measurement of a separate current, namely,

the current to the lower part of the generator, may be effected before the same enters the said generator.

While the fuel is being blown up to incandescence, the retort is heated by the producer or blast gas formed, by the aid of a secondary air-current, and by means of the hot gases in the heating flues playing around the wall of the retort. Distillation gas is thereby produced from the fresh fuel and this gas must be led away (during the period of blowing the fuel up to incandescence) from the upper part of the retort in the proportion in which it is formed. It is therefore necessary to limit the escape of the gas during the period in which the fuel is being blown up to incandescence in order to enable the removal of the distillation gas to be extended as much as possible over the whole time during which the fuel is being blown up to incandescence, and to constantly measure or adjust (or measure and adjust) the volume of gas drawn off from the retort during such time. The apparatus constructed in this way must consequently be provided with an adjustable gas by-pass of smaller cross sectional area than the main gas outlet.

A portion of the producer or blast gas may however, for the purpose of further assisting the distillation of the free fuel, be also intentionally passed through the fuel in the retort, during the period of blowing the coke up to incandescence. This also is rendered possible by suitable adjustment of the previously mentioned by-pass in the gas outlet. In this case naturally gas not wholly free from nitrogen will be obtained but, the amount of nitrogen contained in the gas is small considering the short length of time during which the fuel is being blown up to incandescence.

To carry out my process and its various modifications the apparatus illustrated in vertical section in the annexed drawing can conveniently be employed. 1 is the generator chamber which is heated by hot air blast supplied thereto from underneath by a valve 2. The producer or blast gas formed escapes through the slots (or openings) shown at 3 into the heating flue 4 where it is burned with air supplied through the valve 5 so that the combustion gases sweep through the heating flues 4, 6 and 7 and then pass into the steam superheater 8. The waste gases escape through the opened waste gas conduit 9 into the chimney 26.

In cases where, for the purpose of obtaining a higher yield of ammonia the temperature in the distillation retort 16 is to be lower, only a portion of the air necessary for complete combustion is blown in through the valve 5, the remainder of the air entering through the valve 10 into the steam super-

heater 8, to effect complete combustion of the producer gas.

Between the heating flues 7 and the steam superheater 8 is placed a valve device 11, which is opened while the fuel is being blown up to incandescence and is partly closed during the steam blowing period.

The water gas is produced by the admission of steam at 12 into the steam superheater after the shutting off of the air supplies at 5 and 10 and after shutting the waste gas conduit 9. In 8 the steam is heated up on the fireclay bricks built into it, and a portion of the superheated steam now passes through the pipe 13 and the steam throttling device 14 into the lower part of the water gas generating chamber 1. Another portion of the steam passes out of the superheater 8 through a partially closed valve 11, and also through the by-pass (adjustable at 15) into the heating flues 7, 6 and 4 and then through the slots 3 into the distillation chamber or retort 16 where it mixes with the water gas formed in the generator in consequence of the steam admitted at 14, and both the water gas and the steam admitted at 3, effect the gasification of the fresh fuel intermittently supplied through the charging hopper 17.

The gas mixture escapes through the ascension pipe 18 into the hydraulic main 19. This latter contains the gas outlet pipe 20 which can be shut off by means of the rising and falling bell 21.

If no steam is to be admitted at the bottom, but the production of water gas is to take place in the generator 1, solely by the steam entering through the slots 3, then the throttling device 14 is entirely shut off and the steam passes partly through the retort 16 from the bottom to the top thereby degassing the fuel contained in the said retort and partly through the generator chamber 1 from the top to the bottom, so that water gas may be taken off at 22 in the lower part of the generator by a pipe furnished with a valve 22' while a mixture of water gas and distillation gas may be drawn off from the distillation chamber at 18. In order to make the steam pass upwardly through the retort 16 and downwardly through the generator chamber 1, then at the same time the regulating devices 21, 23 and 22' must be properly adjusted.

While the fuel is being blown up to incandescence this latter valve 22' is closed in all cases, while it is not absolutely necessary to entirely close the steam throttling device 14, as only a very small portion of the air supplied through the valve 2 will escape through it and pass into the steam superheater 8, where it will assist combustion.

In order to also enable the distillation gases to be taken off through an outlet pipe

of smaller cross sectional area than the main gas outlet as hereinbefore described during the period of blowing up to fuel to incandescence, the rising and falling bell 21 in the hydraulic main is closed and a bypass pipe which is provided with a controlling cock 23 and any suitable throttling device 24 for measuring the velocity of the gas current (for example by measuring the difference of pressure) allows the gas in the hydraulic main 19 to escape into the gas outlet 20.

The coal distillation gases being lighter in weight than the producer gas, the former accumulate in the upper part of the distillation chamber or retort 16. Therefore if during hot air blasting, the cock 23 is throttled to such an extent so as to allow only the volume of distillation gas that is evolved in the distillation chamber to pass therethrough, the said gases will escape into the outlet 20 without any appreciable admixture of producer gas therewith. If the throttling of the cock 23 is increased the distillation gases, notwithstanding their being lighter than the producer gas, are to some extent forced downwardly and escape from the distillation chamber 16 through the slots 3 into the heating flue 4, assisting in the external heating of the distillation chamber. If the cock 23 is opened to such an extent as to allow the passage therethrough of more than the whole volume of the distillation gases, a certain amount of producer gas is drawn through the retort 16 with the distillation gas. In this event the process of complete distillation in the retort will be produced by the high temperature of the producer gas. It is therefore important to constantly measure the amount of gas passing through the by-pass which connects the hydraulic main 19 and the gas outlet 20; for which purpose a throttling is effected at 24, which indicates, by means of a differential pressure gauge 25, the velocity of the gas current.

I claim:

1. A process of producing a gas substantially composed of water gas and distillation gas from bituminous fuel which comprises establishing and maintaining a bed of incandescent coke in a gas generating chamber and a superimposed mass of bituminous fuel to be distilled upon the same in immediate contact therewith in a distillation chamber, (a) blowing air through the incandescent coke to form producer or blast gas, burning at least a part of the said producer gas in flues surrounding the said distillation chamber, (b) passing steam through the said flues thereby superheating the steam and introducing it at about the junction point of the distillation chamber and the gas generating chamber, passing a part of this steam through the mass of the

fuel in the distillation chamber and simultaneously passing the other part of this steam downwardly through the incandescent coke in the gas generating chamber, alternately repeating steps (a) and (b) while drawing off the resulting mixture of water gas and distillation gas from the distillation chamber, separately drawing off the water gas formed in the gas generating chamber from said chamber, and replenishing said fuel to maintain both the fuel and the incandescent coke.

2. A process of producing a gas substantially composed of water gas and distillation gas from bituminous fuel which comprises establishing and maintaining a bed of incandescent coke in a gas generating chamber and a superimposed mass of bituminous fuel to be distilled upon the same in immediate contact therewith in a distillation chamber, (a) blowing air through the incandescent coke to form producer or blast gas, burning at least a part of the said producer gas in flues surrounding the said distillation chamber, (b) passing steam through the said flues thereby superheating the steam, introducing the steam at about the junction point of the distillation chamber and the gas generating chamber, passing the steam through the mass of the fuel in the distillation chamber and simultaneously passing superheated steam at about the bottom of the incandescent coke in the gas generating chamber, alternately repeating steps (a) and (b), drawing off the resulting mixture of water gas and distillation gas from the distillation chamber, and replenishing said fuel to maintain both the fuel and the incandescent coke.

3. A process of producing a gas substantially composed of water gas and distillation gas with an admixture of producer or blast gas from bituminous fuel which comprises establishing and maintaining a bed of incandescent coke in a gas generating chamber and a superimposed mass of bituminous fuel to be distilled upon the same in immediate contact therewith in a distillation chamber, (a) blowing air through the hot coke to form producer or blast gas, passing a portion of the said hot producer gas through the fuel in the distillation chamber and thereby subjecting the said fuel to an additional heating, burning simultaneously another portion of the said producer gas in flues, surrounding the said distillation chamber, (b) passing steam through the said flues, thereby superheating the steam and introducing it at about the junction point of the distillation chamber and the gas generating chamber, passing it through the mass of the fuel in the distillation chamber and simultaneously passing superheated steam at about the bottom of the incandescent coke in the gas generating chamber, alternately

repeating steps (a) and (b), drawing off the resulting mixture of water gas and distillation gas and producer or blast gas from the distillation chamber, and replenishing said fuel to maintain both the fuel and the incandescent coke.

4. A process of producing a gas substantially composed of water gas and distillation gas from bituminous fuel which comprises establishing and maintaining a bed of incandescent coke in a gas generating chamber and a superimposed mass of bituminous fuel to be distilled upon the same in immediate contact therewith in a distillation chamber, (a) forming producer or blast gas by blowing air through the said incandescent coke, leading off the distillation gas

evolved in the distillation chamber during the said blowing period from a hydraulic main by means of a by-pass of smaller cross 20 sectional area than the main gas outlet, the said by-pass establishing communication between the said hydraulic main and the main gas outlet, (b) introducing superheated steam in the gas generating chamber, passing the resulting water gas through the distillation chamber, drawing off a mixture of water gas and distillation gas from the said distillation chamber, repeating steps (a) and (b), and replenishing said fuel to maintain 25 both the fuel and the incandescent coke.

In testimony whereof I have signed my name to this specification.

PROF. DR. HUGO STRACHE.
